UNITED STATES PATENT OFFICE.

ROLLAND H. MCCOY, OF MONMOUTH, ILLINOIS.

JAR AND CLOSURE THEREFOR.

SPECIFICATION forming part of Letters Patent No. 778,989, dated January 3, 1905.

Application filed April 14, 1904. Serial No. 203,193.

To all whom it may concern:

Be it known that I, ROLLAND H. McCOY, a citizen of the United States, residing at Monmouth, in the county of Knox and State of Illinois, have invented certain new and useful Improvements in Jars and Closures Therefor, of which the following is a specification.

The invention relates more particularly to fastening devices for securing the covers or lids of jars or bottles to the necks thereof, first by a minor degree and finally by a maximum degree of pressure, and to provide these means constitutes the principal object of the invention.

Another object of the invention is to provide a device of the kind wherein all of the fastening devices are entirely beneath the upper surface or top of the lid and out of the way for convenience and facility in packing or shipping.

A further object is to provide a jar and fastening by the use of which the process known as "cold canning" or vacuum processing may be successfully accomplished.

A still further object is to provide a spring-fastener which may be readily, quickly, and easily applied to or detached from the jar without danger of injury to the hand of the operator and without tools.

Other objects of my invention consist in novel structural features and combinations of devices, the operation of which devices separately and in combination will be found hereinafter fully described, and the novel combinations of which devices are pointed out in the claims hereto appended.

Mechanism showing the arrangement, connection, and mutual relationship of the parts forming the subject-matter of my improvements is illustrated in the accompanying drawings, which are made a part of this specification, and in which—

Figure 1 is a central sectional view of one form of my invention, parts of the jar broken away; Fig. 2, a similar and preferred view of the device; Fig. 3, a top plan of the construction shown in Fig. 2; Fig. 4, a top plan of the construction shown in Fig. 1; Fig. 5, a plan of the lever; Fig. 6, a section of the loop of the fastener in its drawn or taut po-

sition; Fig. 7, a top plan, partly broken away, of the lid, showing grooves therein; Figs. 8 and 9, modifications of the lever; Fig. 10, a plan, seen from below, of a spanner; Fig. 11, a side elevation of the spanner; Fig. 12, a 55 modification of the lever; Fig. 13, a plan view of the same, and Fig. 14 another modification of the lever.

Referring to the drawings by letters, the same letter indicating the same part in the different figures thereof, A represents a jar or bottle which is preferably formed at its upper part with a broad neck having a shoulder a. The upper face of the neck of the jar forms a seat for a rubber packing-ring or 60 gasket a'. 65

B is the lid or cover, provided with a raised central part or button b, having notches or depressions b' in its upper face and preferably intersecting each other at right angles, as shown 70 best at Fig. 7. The lid shown at Fig. 1 has an upwardly-extended annular portion B', an inclined bearing or face B'', a peripheral flange B'', a concave portion B'', and an annular depending flange B'', which projects into the neck 75 of the bottle.

C is a lever formed from metal and has a handle c, an enlarged part c', a substantially elliptical aperture or slot c'' centrally thereof, and in the sides of the slot are niches c''. 80

D represents a transverse metal fastener, preferably of spring-wire, and may be of any desired form in its cross-section. It is bent at or near its mid-length to form a depending loop D', the vertical sides D'' of which are 85 parallel and the points D''' of which are spaced a distance apart. Its outer portions or arms are bent at the points D''' more or less at right angles to the vertical wires D'' of the loop D', approximately horizontally and outwardly to 90 a point d, thence downwardly at an angle to a point d', thence approximately horizontally to a point d'', thence downwardly to a point d''', and thence inwardly to its ends d'''. 95

E F are plates of metal, each having a slot 95 c'', niches c''', and eyes c''', which eyes are engaged by studs h on a spanner H of ordinary construction. These last-named parts are modified forms of the lever C, have the same functions, and their operations will be appar- 100

ent when the operation of the lever is understood. In some forms of plates which may be used with my improvements the eyes are omitted, and a wrench or any other suitable device may be used to give an entire or only a partial revolution to the plates, as will be hereinafter described.

The construction at Fig. 2 illustrates a lid identical with the construction shown at Fig. 1, except that the inclined plane face B^2 of the latter is a straight, convex, or concave face B^2 in the former and that notches G are cut in the face of the portion B' and that in Fig. 2 concentric beads a^3 are shown on the lower face 15 of the flange B^3 . The spring-fastener shown in said figure is also very similar to the one shown in Fig. 1. In the former the loop is formed and the wires bent outwardly as in the latter, thence downwardly and outwardly 20 at an angle, thence downwardly, and thence inwardly to its ends. The last inward bend of the wire in either case lies in a plane approximately parallel with the transverse arms thereof, which extend outwardly from the 25 points D^3 of the loop. It will be apparent that in the construction shown at Fig. 2 the transverse arms D lie wholly within the notches G and beneath the upper surface of the lid, thus serving a useful purpose in shipping, 30 crating, packing, &c. The lids or covers shown in Figs. 1 and 2 may either or both have grooves or filets G intersecting or dividing the upwardly-extending annular shoulder B' for a purpose hereinafter described.

35 So far as known to me no device heretofore employed has been successful when the process known as "cold canning" or vacuum processing has been used. While the use of the present invention makes an absolute success in preserving the article or compound when said process is used, it is nevertheless equally efficient in canning hot articles or materials, whether fruits, meats, soups, vegetables, or other commodities.

40 In cold canning or vacuum processing (the present invention being used) the article to be conserved or preserved is placed in the jar A , either in a cooked or uncooked condition, but cool or cold. The lid B is then put in place, 45 with the packing-ring a' interposed between the flange B^3 and the upper face of the neck of the jar or bottle. The fastener D is then forcibly sprung into the position shown by full lines at Figs. 1 and 2, with the lower portions 50 of the loop D' resting in the grooves b' in the button b on the lid B to prevent the loop turning or twisting the horizontal portions thereof, as shown at Fig. 1, a slight distance above the member B the points d' on 55 the beveled face B^2 and the ends d^4 resting beneath the shoulder a . The force required to spring the fastener into the above-described position will exert a mean degree of pressure 60 on the packing-ring sufficient, in fact, for 65 ordinary purposes, but not sufficient to pre-

clude air or gases entering into or escaping from the jar when under atmospheric pressure, but at the same time causing an atmospheric seal to be produced, as will be described hereinafter in connection with the description of the process as known as "hot canning." The jars and contents are then placed in an exhaust-retort and the air exhausted from the package. After the air has been exhausted as last described and the package removed from the exhaust-retort the atmospheric pressure on the lid and the spring-pressure of the fastener on the packing-ring will form a seal which, were it not for the fact that it might be easily disturbed by slightly 70 displacing the lid, would suffice for ordinary canning; but it is then desirable, if not absolutely necessary, to exert an additional pressure or force on the lid without turning it and disturbing the seal, and this I accomplish as 75 follows: The lever C being in the position shown by full lines, with the vertical parts D'' of the loop D' resting in the ends of the elliptical slot c^2 and the horizontal portion of the loop resting in one of the grooves b' in the 80 button to keep it from turning or twisting, the lever is given a partial (it might be an entire) revolution in either direction, as indicated by dot-lines at Fig. 3, which operation, 85 because of the slot having a greater longitudinal than latitudinal or transverse diameter, 90 will draw the points D^3 of the loop closer together, and thus shorten the fastener D , as shown at Fig. 6 and by dot-lines at Figs. 1 and 2. The member D^2 of the loop will, by 95 reason of it being confined within the notches b' , remain stationary, and the depending wires D'' will be engaged by the niches c^3 and the lever and wires be automatically locked thereby in the position shown by dot lines at Fig. 3. 100

The operation above described will not only exert a very great downward force upon the central part or button of the lid through the medium of the loop D' , but the points d' of the transverse arms, Fig. 1, will be drawn upwardly into a higher position on the inclined bearing B^2 , and thus exert an equal and maximum downward force on the outer parts of the lid, thus hermetically sealing the parts and precluding any possibility of air entering 115 the jar. It will be observed that this direct downward pressure on both the center and the outer part of the lid augments and preserves the atmospheric seal.

In the construction shown at Fig. 2 the extended and inclined arms K of the fastener when the points D^3 thereof are drawn toward each other will slide upwardly over the bearings y formed by the bottom of the notches G in the shoulder B' , and the effect or result 125 will be the same as illustrated in Fig. 1 of the drawings and as hereinbefore described.

In the process known as "hot canning" the article to be canned may be placed in the jar and both raised to a higher degree of 130

temperature or the article may be placed in the jar in a heated condition and the jar cold. In either of said cases the lid and gasket are first put in place and the fastener sprung into its first position, thus exerting one degree of pressure. As the jar and contents cool the contained air becomes rarefied, and because of this rarefied condition the pressure of the external air produces an atmospheric seal. 5 After the jar and contents are cooled it is desirable, if not indispensable, to exert a further and greater pressure, and this is accomplished by the operation hereinbefore described of drawing the proximal points D³ of 10 the loop closer to each other and exerting a direct pressure downwardly and without disturbing the atmospheric seal. Returning the lever to its first position will relieve the spring from tension and permit the parts to be 15 20stantly separated from each other and the cover to be removed from the jar for access to the contents.

In the modifications at Figs. 8 and 9 I have shown two forms of plates which may be used 25 instead of the lever C. The studs h h on the spanner H are engaged with the eyes c⁴ in the plates E F, and said plates are rotated in the same manner and for the same purpose as is the lever.

30 In Fig. 12 I have shown a bent lever for use on very small packages and at Fig. 14 a double-ended lever of the first order.

I desire it understood that I do not limit my claims to the method shown of securing the 35 ends of the fastener to the jar. Recesses may be provided on diametrically opposite sides of the jar or the neck thereof, into which said ends may be sprung, or they may be secured to the jar in any desired or preferred manner. 40 Other forms of plates and levers than what shown may be used if desired, the essential feature of this part of my invention being the slot and the niches c³ therein.

It is desirable in devices of this character 45 that the fastening and locking parts lie in positions where they are not liable to accidental displacement. It is also very desirable in shipping, crating, or displaying the packages that they occupy as little space as possible 50 and that the jars may be packed with their tops confronting or, again, with the top of one resting on the bottom of another. To these ends I have provided a lid constructed as shown in Fig. 2, wherein the face B' is 55 intersected by notches or grooves G on diametrically opposite sides thereof, and which grooves may be of any desired number, but it is essential that they register with the grooves b' in the button b. So constructed, 60 each and every part of my fastening device lies beneath the upper surface of the lid, not only out of danger of becoming displaced or loosened, but the jars may be packed closely together in any desired manner without danger of breaking.

The advantages of the invention will be apparent and the operation will be understood from the foregoing description, it being particularly noted that various changes may be made in the details of construction without departing materially from the general idea involved.

Having thus described my invention, what I claim as new, and desire to secure by Letters Patent, is—

1. In a device of the character described, a jar, a cover therefor, a spring-clamp having its ends engaged with the neck of the jar and its mid-length portion bent to form a depending loop which rests on the upper surface of 80 the cover, the upper portions of said loop being normally spaced apart, a lever having an elliptical slot therein and having niches at the minor diameter of said slot, the depending wires of said loop passing through and 85 engaged by said slot, and said lever adapted to be turned to bring the upper portions of the loop into close proximity to each other and the niches into locking engagement with the depending wires, substantially as and for 90 the purpose specified.

2. In a device of the character described, and in combination, a jar having a shoulder on the neck thereof, a lid having an upwardly-projecting central portion, and having notches in said portion transversely thereof, an upwardly-extended annular portion, having notches registering with the notches in said central portion, a spring-fastener having transverse arms, its mid-length portion bent 100 to form a depending loop, the lower part of which rests in the notches in the central part of the lid, the transverse arms thereof seated in bearings formed by the notches in the annular portion and the ends thereof engaging 105 the shoulder on the neck of the jar, all of the fastening parts beneath the upper surface of the cover, substantially as described and for the purpose specified.

3. In combination, a jar having an annular shoulder about its neck, a cover therefor having a button projecting upwardly from its central part, and having grooves in the upper face thereof, an annular concaved portion surrounding the button, an upwardly-extended shoulder encircling said portion, said shoulder having lateral grooves therein registering with the grooves in the button, and a peripheral flange adapted to be seated on the shoulder on the jar, with a transverse spring-clamp the ends of which engage a part of the jar, said clamp having transverse arms sliding on a bearing formed by the bottoms of the notches in the shoulder, and having a depending loop at its mid-length, the horizontal portion of which rests in the grooves in the button, a slotted lever having niches at the minor diameter of the slot, the depending loop passing through said slot, and the lever adapted to be revolved to bring the upper portions of 130

the loop into closer relation to each other, and the niches adapted to hold them in said position, substantially as described.

4. In an apparatus of the character described, a jar, a spring-fastener comprising members adapted for engagement with a part of the jar, transverse members, inclined members, and a depending loop at its mid-length, a lid having a button projecting upwardly centrally thereof, and having a groove in the face of said button, in which groove the depending loop rests, an annular shoulder B' exterior to the button, and a concaved portion between them, said shoulder having grooves intersecting it, registering with the grooves in the button and forming bearings on which the inclined arms or members slide, and means for drawing parts of the depending loop into closer relation to each other, thereby con-

tracting and shortening the fastener, substantially as and for the purpose specified.

5. A jar-cover having an upwardly-projecting centrally-disposed member, and having grooves or defiles in the upper face thereof, an annular concaved member surrounding said central member, an upwardly-projecting annular member encircling the concaved member, and having intersecting grooves in the face thereof, registering or concurrent with the grooves in the central member, a peripheral flange exterior to the last aforesaid member, and a member projecting downwardly and inwardly from said flange, substantially as described.
